United States Patent Office

Des. 208,356

Patented Aug. 22, 1967

208,356

EXPANSIBLE CAMPER BODY

Joseph E. Oliver, Le Grand, Calif., assignor of twenty percent to Lester J. Gendron, Madera, Calif.

Filed Aug. 2, 1966, Ser. No. 3,312

Term of patent 14 years

(Cl. D14—3)

FIG. 1.

FIG. 2.

FIG. 3.

FIG. 4.

FIG. 5.

FIG. 6.

FIGURE 1 is a side elevational view of an expansive camper body showing my new design, the opposite side being substantially the same in appearance;

FIGURE 2 is a perspective view thereof in expanded position;

FIGURE 3 is a front elevational view of FIGURE 2;

FIGURE 4 is a top plan view of FIGURE 2;

FIGURE 5 is a side elevational view of FIGURE 2, the opposite side being substantially the same in appearance; and,

FIGURE 6 is a rear elevational view of FIGURE 2.

The vehicle shown in broken lines in FIGURES 1 and 2 is included for illustrative purposes only.

I claim:

The ornamental design for an expansive camper body, as shown and described.
